UNITED STATES PATENT OFFICE.

JOHN W. LAUREN, OF STERLING, ILLINOIS.

APPARATUS FOR PRODUCING ELONGATED METAL FORMS.

Application filed July 15, 1922. Serial No. 575,268.

To all whom it may concern:

Be it known that I, JOHN W. LAUREN, a citizen of the Republic of Finland, and a resident of the city of Sterling, in the county of Whiteside and State of Illinois, have invented certain new and useful Improvements in Apparatus for Producing Elongated Metal Forms; and I do hereby declare that the following is a full, clear, and exact description of the same, reference being had to the accompanying drawings, and to the numerals of reference marked thereon, which form a part of this specification.

This invention relates to a method of making wire or rods of different form and an apparatus therefor.

In the wire manufacturing industry at the present time, the billets are heated in a furnace and passed through the reducing or breaking down rolls and then through the finishing rolls. This operation requires a large number of passes or rolls, sometimes as many as twenty or more before the wire is completed. To reduce the number of passes through which the billet and wire must pass in the interest of time and labor and the avoidance of the usual cobbles or waste caused by the breaking down rolls has been a problem in the art.

It is an object of this invention to solve this problem by rolling the billets into cylindrical form simultaneously piercing or axially perforating the same and spirally cutting the perforated cylindrical form and rolling the spirals into the finished product.

It is a further object of this invention to provide apparatus and machinery for accomplishing this purpose.

With these and other objects in view which will become more apparent in the following description and disclosure, this invention involves the novel method and mechanism hereinafter described and more particularly pointed out and described in the appended claims.

In the accompanying drawings which illustrate a preferred embodiment of this invention and in which similar reference numerals refer to similar features in the different views:

Figure 1 is a top plan view of the apparatus or machinery used.

Figure 2 is an elevational view thereof.

Figure 3 is an elevational view of the cutting mechanism in operation upon a tube.

Figure 4 is a top plan view of the cutting mechanism in operation.

Figure 5 is an end elevational view of the cutting mechanism.

In carrying out my method, I first heat a billet to the proper temperature, then simultaneously roll it into cylindrical form and pierce or axially perforate the same and cut the cylindrical perforated billet into a spiral and straighten and form the spiral into the desired shape and diameter. While the method and apparatus are illustrated in connection with the manufacture of wire, the method is susceptible of use in producing rods, bars or flats or hexagonals or other form.

In the drawing, I have illustrated an apparatus for carrying out this method. In Figures 1 and 2, I have shown a piercing machine 1 having rolls 2 between which the heated billets are successively passed and rolled for turning the same into cylindrical form. A perforating head 3 is supported in this machine and as a billet is rotatably forced through the machine, it will be forced over this head, and become perforated in an axial direction. This piercing machine is well known in the art and needs no further description.

Cutting mechanism in the form of a pair of cooperating rotary cutting elements or disks 4 are supported upon the shafts 5 and 6 journaled in a frame 7 having a bifurcation 8 through which the shafts 5 and 6 extend. A pair of intermeshing gears 9 are supported upon said shafts, one upon each shaft in said bifurcation for causing simultaneous rotation thereof. The frame 7 is provided with a second bifurcation whereby a spaced support 7^a is formed upon which a motor 10 may be mounted, the shaft 11 of which being clutched to the shaft 6. It will be apparent that operation of the motor 10 will simultaneously rotate the shafts 5 and 6 with the cutting elements thereon.

The cutting disks 4 are oppositely bevelled and their axes are spaced apart a distance less than the diameter of the disks so that the cutting edges will slightly overlap as shown in Figure 3. The cutting mechanism is obliquely supported with respect to the axis of the billet 12 passing through the piercing machine 1 as shown in Figure 1 and is so positioned that the cutting elements will engage the inner and outer sur-

face of the wall of the perforated end after quality of finished product is obtained according to this method.

In briefly summarizing the operation of the apparatus shown, it may be stated that the heated billets are successively passed through the piercing machine which rotates each billet between forming rolls and perforates it in an axial direction. As the billet is advanced through the piercing machine, it constantly rotates and when the lower end which is first perforated engages the rotary cutting disks 4 operated by the motor 10, the process of cutting the tubular portion into a spiral strip begins. This spiral strip which is designated by 12^a may be manually fed to the finishing rolls 13—15 when it is of sufficient length to extend to said rolls.

The action of the finishing rolls upon the strip 12^a will aid in the rotation of the billet in the piercing machine as is obvious. As the billet 12 is fed further through the piercing machine, it is being further perforated and cut into a spiral strip and at the same time, the finishing rolls are rolling the spiral into final form.

It will accordingly be apparent that the described apparatus simultaneously forms a billet into tubular shape, and cuts the same into a spiral which is passed through the finishing rolls as fast as it is cut.

I am aware that numerous details of construction may be varied through a wide range without departing from the principles of this invention, and I therefore do not purpose limiting the patent granted otherwise than necessitated by the prior art.

I claim as my invention:

1. In an apparatus of the class described, the combination with mechanism for rolling and axially perforating a billet, of mechanism for spirally cutting the hollow billet, and finishing rolls for reducing and forming the spiral into the desired product.

2. The combination with mechanism for rolling and axially perforating a billet, of rotary cutting elements adapted for spirally cutting the billet as the same is being perforated, and finishing rolls for reducing and forming the spiral.

3. The combination with a piercing machine, of cutting mechanism adapted for spirally cutting a billet passed through the piercing machine, and mechanism for reducing and forming the spiral into the desired product.

4. The combination with mechanism for rolling and axially perforating a billet, of cooperating rotary cutting elements adapted for spirally cutting the billet as it is being perforated, and means for reducing and forming the spiral into the desired product.

5. The combination with a piercing machine, of rotary cutting elements positioned at an inclined angle with respect to the axis of the piercing machine, and finishing rolls

45 It will be understood that different sized apertures may be pierced through the tube 12 to obtain different thicknesses of metal and by varying the inclination of the cutting elements, different widths of metal may 50 be secured, so that the number of sets of finishing rolls 13—15 need not be very great to produce the desired form.

It will be appreciated that by piercing the billet and rolling it into cylindrical form 55 and cutting the same into the desired sized strip, the breaking down rolls for the billets now commonly used are eliminated and the cobbles that usually occur therein are avoided and the number of finishing rolls 60 is greatly reduced. It is further manifest that the longitudinal slivers which usually occur in rolled wire, bars or the like, will be practically eliminated since the hollow billet 12 is cut transversely of the direction 65 that the slivers usually extend so that a bet-

arranged with their passes in alinement at right angles to the axis of the cutting elements for the purpose described.

6. In a wire making machine, mechanism for axially piercing a billet, rotary cutters arranged obliquely to the axis of said mechanism for spirally cutting the billet and mechanism for reducing and finishing the cut spirals.

7. In a wire making machine, mechanism for piercing a billet, cutters for spirally

shearing the hollowed billet as it is being pierced and finishing rolls for rolling and reducing the spirals.

8. The method of making wire which consists of simultaneously piercing a billet, cutting the pierced portion into spirals and reducing and finishing the spirals. 15

In testimony whereof I have hereunto subscribed my name.

JOHN W. LAUREN.
